US0D1086158S

(12) **United States Design Patent** (10) Patent No.: **US D1,086,158 S**
Bonow (45) Date of Patent: ** Jul. 29, 2025

(54) **DISPLAY PANEL WITH A GRAPHICAL USER INTERFACE**

(71) Applicant: **BELIMO HOLDING AG**, Hinwil (CH)

(72) Inventor: **Hendrik Bonow**, Zurich (CH)

(73) Assignee: **BELIMO HOLDING AG**, Hinwil (CH)

(**) Term: **15 Years**

(21) Appl. No.: **29/883,584**

(22) Filed: **Jan. 31, 2023**

Related U.S. Application Data

(62) Division of application No. 35/513,312, filed on Jul. 2, 2021 (U.S. filing date under 35 U.S.C. 384), and having an international filing date of Jul. 2, 2021, now Pat. No. Des. 996,989.

(57) **CLAIM**

The ornamental design for a display panel with a graphical user interface as shown and described.

DESCRIPTION

The FIGURE is a front view of a display panel with a graphical user interface, showing the design.

The broken line in the FIGURE shows a display screen or portion thereof, and portions of the graphical user interface that form no part of the claimed design.

1 Claim, 1 Drawing Sheet
